UNITED STATES PATENT OFFICE.

JOHN H. STONE, OF BUFFALO, NEW YORK.

AWNING FASTENER.

Application filed January 9, 1925. Serial No. 1,504.

This invention relates to an improvement in an awning fastener, and more particularly to a fastener of that type comprising two parts, one of which is adjustably secured to the awning while the other is rigidly fixed to the wall of the building on which the awning is to be installed.

An awning fastener of this general type is shown in my Patent No. 1,492,405, dated April 3, 1924, and this invention relates to an improvement upon the construction on which that patent was based incorporating certain new features which are found to be of considerable advantage in the art.

The primary object of this invention is to provide an awning fastener of the type disclosed in which the part rigidly fixed to the building and hereinafter referred to as the bracket is provided with a pocket which receives the tongue of the member adjustably secured to the awning, and hereinafter referred to as the clamp and holds it against any movement longitudinally of the bracket while the parts are in the assembled position.

A further object of this invention is to provide in an awning fastener of this type eyes on the bracket for receiving the pulley blocks rather than providing eyes on the clamp as disclosed in my patent referred to above.

Other objects of this invention will appear from a consideration of the following description taken in connection with the drawings which form a part thereof, and in which—

Fig. 1 is a front elevation of one type of bracket rigidly fixed to the wall of the building;

Fig. 2 is a similar view of another form of bracket which can be used when desired;

Fig. 3 is a front elevation of the clamp which is adjustably secured to the awning;

Fig. 4 is a side elevation of such clamp;

Fig. 5 is an enlarged sectional view of an awning installation including the form of bracket shown in Fig. 1; and

Fig. 6 is a view similar to Fig. 5 of an awning installation including the form of bracket shown in Fig. 2;

Referring to the drawings, the reference numeral 10 is employed to designate the wall of a building on which a bracket 11 is rigidly fixed by screws 12, directly under a projecting cornice 13. The bracket shown in Fig. 1 is provided with a base 14, which is fixed

against the wall of the building by the screws 12. Projecting from and integral with the base 14 is an arm 15, the portion 16 connecting the base 14 and the arm 15 being curved outwardly in order to space the arm 15 from the wall of the building, as shown in Fig. 5. In the upper edge of the arm 15 is provided a pocket defined by a notch 17, the purpose of which will be disclosed later. It will be noted that the upper edge of the arm 15 beyond the notch 17 is somewhat lower than the upper edge of the base 14. Formed at the lower edge of the base 14 below the screws 12 are eyes or hooks 18, which receive pulley blocks 19, as shown in Fig. 5.

The type of bracket shown in Fig. 2 differs from that previously described in that the base 21 of the bracket 20, through which screws 22 pass to fix the bracket on the wall of the building 10, comprises separated portions 21^a between which is formed an integral intermediate member 23, hooped to form a pocket 24 for a purpose to be described later. At the lower edges of the base portions 21^a below the screws 22 are formed integral eyes or hooks 25, which are adapted to receive the pulley blocks 19, as are shown in Fig. 6.

It will be noted that the bracket 20 is used when there is no cornice to be considered so that the awning can be installed from above. The brackets are permanently fixed to the building and need not be removed when the awning is taken down. The great advantage of this feature has been pointed out at considerable length in my patent, and attention thereto is respectfully drawn.

The clamp 26 which forms the other part 95 of the fastener has a front portion 27, which encloses and grips the awning around the stiffening rod or bar 28, as shown in Figs. 5 and 6. This bar is inserted through a loop or hem 29 formed in the upper edge of the 100 awning 30 in the usual manner. The clamp 26 is preferably made of spring metal so that it will tightly engage the bar and prevent any involuntary shifting in the clamps. The rear wall of the clamp 26 is slotted to 105 form a tongue 31 and side strips 32, the tongue 31 being bent away from the side strips 32, as shown particularly in Fig. 4 to provide a space 33 therebetween.

In both types of bracket the eyes for the 110 pulley blocks 19 are located below the fastening screws and out of alignment with

the pockets. Thus any strain is taken directly by the screws and base, and is not transmitted to the awning and clamps through the pocket provided portion.

6 The method of installing awnings equipped with fasteners made in accordance with this invention is as follows: The brackets are first rigidly fixed to the wall of the building, either form being used except that, 10 when the awning is directly below a cornice, the bracket 11 must be installed as shown in Figs. 1 and 5. The clamps 26 are secured to the awning by being slipped along the rod 28 and loop 29 into a position corresponding to the location of the brackets already installed on the building. As pointed out above, the clamps 26 are preferably of 15 spring metal and hold the rod 28 tightly. The pulley blocks 19 are first hung on the eyes 18 or 25 and then the awning is mounted upon the brackets, the tongues 31 entering the pockets of the brackets so that the awning is held in the proper position. If the brackets 11 are used, the clamps are slid 20 longitudinally over the arms 15 until the tongues 31 are over the pockets defined by the notches 17 and then the awning is lowered so that the tongues enter the pockets, while if the brackets 20 are used the tongues 25 31 are dropped directly into the pockets 24. Either form of pocket will receive the tongue 31, and by reason of its construction, as pointed out above, prevent the clamp from shifting longitudinally out of engagement 30 with the bracket.

The side strips 32 lie in front of the arms 15 if the bracket 11 is employed or in front of the intermediate portion 23 if the bracket 20 is employed. The space 33, between the 40 tongue and the side strips, is preferably made slightly less than the thickness of the bracket so that the clamps must be forced into place, and will be held there by the contact of the tongue and side strips with the 45 pocket provided portion.

While two embodiments of this invention have been shown and described, applicant

is not limited thereto, since it is obvious that other embodiments can be made without departing from the spirit and scope of this 50 invention as set forth in the following claims.

Having thus set forth my invention what I claim as new and for which I desire protection by Letters Patent is:

1. An awning fastener comprising a bracket which is rigidly fixed to the building on which the awning is to be installed and a clamp which is adjustably secured to the awning, enclosing the stiffening bar thereof, 60 said bracket having a base through which means are inserted to fix it to the building, eyes on said base below said fixing means for receiving pulley blocks, and a pocket integral with said base and out of vertical alignment with said eyes, and said clamp having its rear wall slotted to form a tongue and side strips, said clamp being mounted upon said bracket by the insertion of said tongue into said pocket, while said side pieces rest upon the outer face of said pocket provided portion.

2. An awning fastener comprising a bracket which is rigidly fixed to the building on which the awning is to be installed and a clamp which is adjustably secured to the awning, enclosing the stiffening bar thereof, 75 said bracket having a base through which means are inserted to fix it to the building, eyes on said base below said fixing means for receiving pulley blocks, an arm integral with said base and projecting therefrom, a pocket defined by a notch in the upper edge of said arm, and said clamp having its rear wall slotted to form a 80 tongue and side strips, said clamp being mounted upon said bracket by the insertion of said tongue into said pocket with said tongue resting in said notch and said side pieces resting upon the outer face of said 85 arm.

In testimony whereof I have affixed my signature.

JOHN H. STONE.
